PISTON AND PISTON PACKING

John L. Harrah, Erie, Pa.

Application November 7, 1949, Serial No. 125,941

14 Claims. (Cl. 309—45)

1

This invention relates broadly to piston packing construction and more particularly to improvement in piston packing construction adapted primarily for use in internal combustion engines.

An important object of this invention resides in the provision of novel means for effecting a more accurate and uniform control of the blow-by and the compression pressure of internal combustion engines.

Another object of the invention resides in the provision of means for removing the oil from the cylinder walls, returning same and retaining it in the crankcase.

These and other objects and advantages of the improved piston packing construction will, however, hereinafter be more fully described.

In the accompanying drawings, forming a part of this application and wherein like numerals are employed to designate like parts throughout, I have shown one embodiment of my invention.

Figure 1 is a front plan view of the piston packing.

Figure 2 is a front plan view of a cylindrical piston especially constructed to receive the present piston packing.

Figure 3 is an end plan view of the back member of the packing.

Figure 4 is a plan view of the back member showing inwardly and outwardly extending offsets.

Figures 5, 6, and 7, respectively, are plan views of the laminae employed in this particular construction.

Figure 8 is a fragmentary front plan view showing the overlapping of the ends of the laminae and also dovetailing of the inwardly and outwardly extending offsets as shown in Figure 4.

Figure 9 is a likened end plan view of the laminae shown in Figures 5, 6, and 7, respectively.

Figure 10 is a top plan view of the piston on line 2—2 of Figure 11.

Figure 11 is a cross sectional view of the piston and the packing.

Although it is to be expressly understood that the piston packing herein described with the provision of laminae is not limited to such construction, as provision is also made for the packing to be made of similar one piece sections as shown in Figure 1.

In this illustrative construction, I have shown a piston packing, generally indicated at numeral 3, associated with the provided packing space 4.

The piston 5 is of an improved construction having the space 4 especially provided for receiv-

ing the piston packing 3 and all will hereinafter be more fully described.

(1) The piston, generally represented by numeral 5, is of one piece, cylindrical construction, having open end wrist pin bosses, skirt portion 1, and head portion 10.

(2) The circumferential, and unobstructed space 4, extending between the outer underneath surface of said head portion 10, and the inwardly extending shoulder of the piston skirt 1, indicated by lines and numerals 18—19, in Figure 2, is especially provided to receive the improved packing means 3.

(3) As it will be noted in the drawings, in Figures 2 and 3, the sides of the skirt portion 1 are cut away from the wrist pin boss sides. The purpose for this is to allow the thrust face sides of the skirt 1, to be placed closer to and to contact the cylinder walls in a straight line.

(4) The construction of this piston is designed, primarily, to receive the improved detachable piston packing or packings 3, and to eliminate the use of rings and ring grooves of the conventional type pistons.

(5) In practice a piston constructed in accordance with the invention has been found to be highly efficient. The weight of the piston is considerably reduced and at the same time the piston has the advantage of being capable of fully withstanding the wear to which it is subjected to, especially, with the elimination of the conventional type piston rings and grooves.

Referring to the packing 3 as shown in the drawings, it will be noted that it includes a back member 6, having laminae 7, 8, and 9 either welded or by other suitable fastening means, substantially and securely laminated onto and extending parallel to said back member 6.

Said back member 6 is of a thin one piece flat semi-circular construction. Each of the outermost ends having an inwardly and outwardly extending offsets 14—15 for the purpose of dovetailing.

The parallel sides 16—17 of said back member 6 are formed to extend upwardly and being so proportioned so as to be snugly received in the inside surfaces of the provided space 4 of the piston neck, indicated by lines and numerals 18—19. Said sides of the back member 6 to extend parallel and adjacent to the inside surfaces of said piston neck 4.

Each of the laminae 7, 8, and 9 are also of thin flat one piece semi-circular construction. Each of the parallel outer edges of each of the laminae are formed to extend upwardly. An

equal number of the upwardly extending edges to slant outward and upwardly and the remainder to slant outward and downwardly. The slant of each of the laminae is illustrated in the cross sectional view in Figure 11 and indicated by lines and numerals 20—21. For the sake of brevity the slanting edges of the laminae will be hereinafter referred to as upwardly slanting fins 20 and downwardly slanting fins as 21.

The flat space 22 between the upwardly extending edges of the laminae is slightly cut away to allow overlapping of the ends of the fins 23—24. The purpose of the overlapping ends is to prevent leakage of the blow-by and the compression pressure between the sections 11, 12, and 13. Overlapping the fins also prevents oil from entering the combustion chamber.

Thus assembled—the semi-circular laminae 7, 8, and 9 are securely fastened to and extend parallel to the semi-circular back member 6. Said back members 6 are positioned circumferentially around said provided space 4 of said piston neck 5. Said off-sets 14—15 are dovetailed as each section 11, 12, and 13 communicates with each other. The slight cut away ends 23—24 of the fins also are overlapped while in this position.

The piston packing 3 is constructed of spring steel or other suitable material assuring a slight flexibility in the fins 20—21 as they contact and rub against the cylinder walls. The upwardly extending fins 20 have a slight flexibility so the downward pressure from the combustion chamber will cause their closer contact with the cylinder walls. These fins would, of course, be known as the compression fins.

The downwardly extending fins 21 have a slight flexibility so they can scrape the oil from the cylinder walls back toward the crankcase. These fins would be known as the oil fins.

As the fins wear against the cylinder walls it would naturally sharpen the edges which will cause a tighter fit while contacting and rubbing against the cylinder walls.

Because of the differences in piston construction, especially where the packing is received, it is necessary to construct this packing in two or more sections. In this application I have shown the illustrative employment of three sections 11, 12, and 13, as shown in Figure 10.

While on the other hand, pistons constructed with removable packing sections would require packing comprising only one circumferential section.

The pistons constructed with the removable packing sections would allow the top portion 10, of the piston to be removable and thereby allowing the said packing carrying section to be removed and replaced from the top of the motor.

For these and other reasons it is to be understood that the illustrative construction shown may be modified in various respects without departing from the spirit and scope of my invention, and it will be understood that it is my intention to include all such modifications in the scope of the appended claims.

What I claim as new and desire to secure by Letters Patent is:

1. In a piston packing, comprising semi-circular laminae and semi-circular back members; said back members being of substantially thin flat one piece construction and whose ends are off-set for the purpose of dovetailing; outside parallel edges of said back members being formed to extend inwardly at ninety degree angles and to extend parallel and adjacent to the inside sur-

faces of said piston neck; said laminae of substantially thin flat one piece construction whose outside parallel edges are formed to extend upwardly, an equal number of said upwardly extending edges to slant outward and upwardly, the remaining edges to slant outward and downwardly; the end space between the upwardly extending edges of said laminae to be slightly cut away for the purpose of overlapping the ends of said edges; said laminae are securely and firmly laminated onto said back members thereby forming upwardly and downwardly slanting fins which form the compression and oil fins of said piston packing.

2. In a piston packing, comprising circular laminae and circular back members; said back member being of substantially thin flat one piece construction and whose ends are off-set for the purpose of dovetailing; the outside parallel edges of said back members being formed to extend inwardly at right angles and to extend parallel and adjacent to the inside surfaces of said piston neck; said laminae of substantially thin flat one piece construction whose parallel outside edges are formed to extend upwardly, an equal number of said upwardly extending edges to slant outward and upwardly, the equal remaining edges to slant outward and downwardly; said laminae are securely and firmly laminated onto said back members, thereby forming upwardly and downwardly slanting fins; said laminae and back members constructed of spring steel or other suitable material assuring a slight flexibility in said fins; the upwardly extending fins having a slight flexibility forms the compression fins and the downwardly extending fins having a slight flexibility forms the oil fins; said flexibility of said fins assures a more accurate and uniform control of the blow-by and the compression pressure and also retains the motor oil in the crankcase as they contact and rub against the cylinder walls.

3. In a piston packing, comprising a back member with right angular inwardly extending edges and off-sets at each end for the purpose of dovetailing; said back member having protruding projections being so proportioned to form substantial fins; said fins being so positioned to form compression and oil fins; said compression fins for the purpose of controlling the blow-by and compression pressure of internal combustion engines, said oil fins for the purpose of scraping the oil down the cylinder walls toward the crankcase; said fins having a slight flexibility to assure a more accurate and uniform control of the blow-by and compression pressure and to retain the oil in the crankcase as they contact and rub against the cylinder walls.

4. In a piston packing, comprising a circular back member; said back member having outwardly extending substantially thin projecting fins; said fins being so proportioned to form the required means for a more accurate and uniform control of the blow-by and compression pressure of internal combustion engines and to retain the motor oil in the crankcase as said fins contact and rub against the cylinder walls.

5. In a piston packing, comprising a substantially thin circular back member; said back member having outwardly extending substantially thin projecting fins; said fins being so proportioned to form the required means for a more accurate and uniform control of the blow-by and compression pressure of internal combustion engines and to retain the motor oil in the crank-

case as said fins contact and rub against the cylinder walls; said fins brought into closer contact with the cylinder walls with the use of a backup spring hidden in back of said back member and communicating with said piston neck.

6. In combination, a piston of substantially thick, cylindrical construction, having wrist pin bosses, skirt and head portions, and packing means of the class described; said packing comprising circular laminae and circular back members; said back member being of uniformly thin, one piece construction and whose ends are offset for the purpose of dovetailing; the outside edges of said back members being formed to extend inwardly and at approximate right angles to said back member, and when assembled said edges to extend parallel and adjacent to the inside surfaces of the space provided which extends circumferentially between said top and skirt portions; said laminae of uniformly thin, one piece construction and whose parallel outside edges are formed to extend upwardly, a number of upwardly extending edges to slant outward and upwardly, and a number of said edges to slant outward and downwardly; said laminae are securely and substantially laminated on to said back members, thereby forming upwardly and downwardly slanting fins; the upwardly extending fins forming the compression fins and the downwardly extending ones forming the oil fins.

7. In combination, comprising a piston of uniformly thick cylindrical construction, having wrist pin bosses, skirt and head portions and a detachable packing or packings; said piston having an upper and lower portion forming the head and skirt sections; sufficient and unobstructed space extending circumferentially between said head and skirt sections to receive said detachable packing or packings; said packing or packings comprising a back member having upwardly and downwardly extending fins; said packing or packings being so proportioned so as to be snugly received in the space provided between said head and skirt sections.

8. In combination, the herein described piston and packing for internal combustion engines, the same consisting of packing and a piston of substantially thick, cylindrical construction, provided respectively with wrist pin bosses, head and skirt sections; the upper periphery of said piston having sufficient space provided between said head and skirt sections to substantially receive said packing means; said packing comprising a substantially thin, semi-circular back member, having uniformly extending upwardly and downwardly extending fins being so proportioned so as to be correctly placed in the cylinders of the internal combustion engines.

9. The herein described piston and packing for internal combustion engines, consists of a piston of substantially thick, cylindrical construction, comprising wrist pin bosses, cylindrical cut away skirt, and a flat circular head portion; said skirt portion having an upwardly extending hollow neck portion being provided especially to receive the said packing; the top of said hollow neck being closed with the head portion being located thereon; the packing consists of a back member with upwardly and downwardly extending fins, said fins being so proportioned so as to be placed in the cylinders of the internal combustion engines.

10. The herein described piston and packing

for internal combustion engines, the same consisting of a piston of substantially thick cylindrical construction, having a detachable head, wrist pin bosses, and a skirt section; said piston having unobstructed, and circumferentially extending space, extending between said head and skirt sections, and being provided especially to receive an improved form of piston packing; said packing of the class described consisting of a back member with a series of laminae being securely and firmly fastened on to said back member, and being so proportioned so as to be placed in the cylinders of internal combustion engines.

11. The herein described piston and packing for internal combustion engines, the same consisting of packing means, and a piston of substantially thick, cylindrical construction, having wrist pin bosses, detachable head and skirt sections; said piston having sufficient and unobstructed circumferentially extending space between the shoulder of said skirt section and the outer underneath surface of said detachable head to receive said packing means; said packing means consisting of a back member of semi-circular construction, and being so proportioned so as to be snugly received in said unobstructed space; said back member having outwardly projecting fins extending upwardly and downwardly to form the required means for a more accurate and uniform control of the blow-by and the compression pressure of the internal combustion engines and to retain the motor oil in the crankcase as the said fins contact and rub against the cylinder walls; said piston packing removable from said piston by removing said detachable head from said piston by removing conventional type fasteners or locking means.

12. In combination, a piston body and a piston packing; said piston packing of one piece circumferential construction having a slot extending therethrough; said packing having a back member with outwardly extending angular edges and upwardly and downwardly extending fins; said upwardly extending fins forming the required means for control of the compression pressure and the blow-by of internal combustion engines; the downwardly extending fins forming the required means for returning the motor oil to and retaining same in the crankcase; the angular edge of said back member and the upwardly and downwardly extending fins being so proportioned so as to be suitably engaged around the space provided on the upper periphery of said piston body.

13. A piston packing of circular construction, being die cast of suitable spring metal and having a back portion with outwardly extending edges; said back portion having upwardly and downwardly extending fin projections communicating therewith; said back portion with outwardly extending edges and upwardly and downwardly extending fin projections being so proportioned so as to be suitably received on the upper periphery of trunk type piston bodies and properly received in the cylinders of internal combustion engines.

14. In combination, a cylindrical piston body and a piston packing; said piston packing being die cast of a suitable packing alloy and comprising a back member with upwardly and downwardly projecting fins communicating therewith; said cylindrical piston of the trunk type construction whose upper periphery is so cut away

and proportioned to properly receive said back member with upwardly and downwardly projecting fins and each being so proportioned so as to be correctly received in the cylinders of combustion engines.
